JOSEPH F. MEYER, OF ORANGE, NEW JERSEY

KNITTING MACHINE

Application filed February 27, 1930. Serial No. 431,700.

This invention relates to knitting machinery.

Special objects of the invention are to provide a machine capable of handling a greater number of strands than has heretofore been possible, which will allow for a greater variety of patterns and the quick and easy changing of the patterns and to provide the machine in a relatively simple and compact form, the capacity and character of work accomplished, considered.

Other desirable objects and the novel features of construction, combinations and relations of parts by which the same are attained will appear in the course of the following specification.

The drawings accompanying and forming part of the specification illustrate one practical commercial form of the invention, but it will become apparent particularly from the broad scope of the claims following that the actual structure may vary as regards this disclosure without departure from the true spirit of the invention.

Fig. 1 is a broken end or front elevation of the machine; Fig. 2 is an enlarged, broken and part sectional detail illustrating particularly the feeding-in action of the pattern links; Fig. 3 is a broken plan view as on substantially the plane of line 3—3 of Fig. 2; Fig. 4 is a broken side view looking toward one of the shifting bar carriers, frame portions and other details of the machine being omitted; Fig. 5 is a cross-sectional view as on substantially the plane of line 5—5 of Fig. 3; Figs. 6 and 7 are sectional details of the link conveyer as on lines 6—6, 7—7 of Fig. 1; Figs. 8 and 9 are broken sectional enlargements of the link feeding and dropping mechanism; Fig. 10 is an enlarged broken sectional detail of one of the spring detents at the foot of the link guide; Fig. 11 is a broken detail of one of the link conveyer chains.

In the general view, Fig. 1, it will be observed that the present machine differs from the standard type of machine first in that instead of a single row there are two rows 15, 16, of the rods or bars carrying the thread tubes 17. These rows are arranged

one above the other and for the sake of greater compactness the bars of the two rows are shown, Fig. 4, as disposed in staggered relation in the vertically sliding supports 18. Because of this staggered arrangement the operating heads 19 on the outer ends of these slide bars are shown as of tapered shape, those of the upper row pointing downward and those of the lower row pointing upward in between the upper heads, in substantially parallel sided relation. This construction and arrangement in turn brings the two rows 20, 21 of the pins for operating the slide bars more nearly into the plane of a single horizontal row, as will be clear from Fig. 4, enabling the use of narrower and smaller backs 22 for carrying the pins.

The usual means, such as a cam 23 and rocker arms 24, 25, may be employed for raising and lowering the slide bar supports 18, Fig. 4. This same view illustrates the general relation of the bed 26, carrying the needles 27, which are advanced by a pusher 28 and returned by a puller 29, also the threads 30 passing down through the reciprocating guide tubes, meeting the warp threads 31 at the needles to form the finished fabric 32.

The pattern links, that is the backs 22, carrying the upper and lower rows in sets of pins 20, 21, are traversed in an orbit by spaced parallel chains 33, 34, supported by upper and lower sprockets 35, 36 on suitably driven shafts 37, 38. At a point in this orbit opposite the slide rods, the links are diverted, one at a time, used to actuate the rods and then returned to the regular orbital travel. The means for accomplishing this comprise in the illustration the open-ended channel guides 39, Fig. 1, substantially tangential to the upper sprockets to receive the backs of the links and inclined downwardly therefrom toward the adjacent side of the machine, the links dropping from these guides one at a time into a horizontal way 40, in which they are advanced by a pusher 41 and then drop into channel ways 42 inclined downwardly and

back into tangential relation to the lower sprockets.

The pusher 41 is shown as a cross head carried by parallel arms 43 sliding in undercut ways 44, in a table 45, said arms being connected at the rear by a link 46 with a swinging lever 47, oscillated by a suitable pitman 48.

Propulsion of the links by the chains is effected in the present disclosure through the medium of lugs or studs 49 on the back of the links which take in between the extension rolls 50, Fig. 11, projecting from the side of and carried by the pivot pins 51 of the chains. To accommodate these lugs the sliding pusher 41 is appropriately recessed, as indicated at 52, Figs. 2, 3, 8, 9, 10, which interfitting arrangement aids in the proper shifting of the links in the horizontal way 40.

Ball point spring detents 53 are shown in Figs. 2, 3 and 10 at the junction of the inclined chute 39 with the horizontal way 40 to restrain and position the bottom link as it slides into the horizontal way under the impulse of the pusher. The side arms 43 of this pusher are indicated in Fig. 2 as being flush with the top of the pusher so as to act as a cut-off preventing the next link from dropping down as the first link is thrust forward by the head of the pusher.

Dash pots 54 are shown in Figs. 1 to 3 and 8 for controlling and cushioning the forward stroke of the links and for returning them back to the dropping out station at the head of the return chute 42, Fig. 9. These dash pots are indicated in Fig. 3 as having pistons 55 and projecting piston rods 56, carrying heads 57 positioned in the horizontal way to engage the end portions of the links. Springs 58 acting on the pistons cause them to closely follow the retreating movement of the pusher head and hence to definitely return the links to the dropping out position, Fig. 9.

To trip the links and drop them out of the grip of the pusher head as they reach the return chute on the back stroke, stripper fingers 59 are shown pivoted at the sides of the horizontal way, adapted to lift and drop behind the links on the forward stroke, Fig. 8, thus to position themselves to act as stops to arrest the return movement of the links at a point over the mouth of the return chute. Fig. 9 shows how the lower tracks of the horizontal way 40 are interrupted at the mouth of the return chute. This gap at 60 permits the links to fall into this chute as the pusher head backs away from supporting engagement with the lugs 49 when the links are caught by the strippers. On the forward stroke however, this gap is of no effect as during such time the links are carried over it supported by their

lug 49 seated in the pockets 52 in the face of the pusher.

It will be understood that the link feeding and circulating mechanism shown at the right in Fig. 1 is repeated in reversed relation at the opposite side of the machine, the parts being so timed that as a link is advanced into one side of the machine, the companion link will also be advanced at the opposite side of the machine, the pins of the links matching in length to effect the requisite traverse of the slide rods carrying the thread guides.

The two rows of rods gives the machine a much greater capacity and the possibility of a much greater variety of patterns than heretofore attainable; the loose or separate form of pattern link enables the machine to be set up with more links more easily and quicker than where the links are connected in a continuous chain as in previous practice and this construction, with the vertical travel of the links provides a more compact assemblage.

The take-off and return chutes 39, 42, confine and guide the links at the inside run of the chains, Fig. 1 and straight channel guides are shown at 61, guiding the links at the outer run, from the lower to the upper sprockets. Suitable guides may be provided about the sprockets such as the inner and outer rows of guide rolls 62, 63, about the upper sprockets, Fig. 1 and 6 and the outer row of guide rolls around the lower sprocket as illustrated at 64 in Figs. 1 and 7. Some of the links may be "blanks" that is without pins as indicated by way of example in Figs. 1 and 2. To enable quick insertion or removal of the links, the guides may be constructed with a "gate" substantially as indicated at 65 in Figs. 1 and 9, this consisting in the illustration simply of a hinged section of the return chute 42, which can be opened up to enable the re-placement or removal of the links.

The arrangement of the reciprocating thread guide bars in the staggered order and one row above the other, with the tappets on the ends of these rods in alternating order and extending toward a common intermediate plane greatly increases the capacity of the machine, disposes this greater number of thread guide bars in a single compact group, which can be properly handled by the lifting and lowering mechanism and enables the pattern links to be made as relatively small light members having narrow backs occupying but small space, so that a great number of them may be employed in the circuit.

What is claimed is:

1. In a knitting machine, the combination of reciprocating thread guide bars arranged in rows, one row above the other, pattern links carrying actuating pins disposed in

superposed rows to cooperate with the superposed row of bars, means for effecting operating engagement of the links with the bars and means for circulating said pattern 5 links to and away from said operating means, said links being unconnected and said circulating means being constructed to handle said unconnected links in serial order.

2. In a knitting machine, the combination 10 with reciprocating thread guide bars, of a series of loose unconnected pattern links for cooperative engagement with said guide bars, means for effecting operative engagement of the links with the guide bars and 15 means for sequentially traversing said loose unconnected links in a circuit to and away from said operating means.

3. In a knitting machine, the combination 20 of reciprocating thread guide bars, a pusher stationed in definite relation to said bars, loose unconnected links adapted to be shifted by said pusher into cooperative relation with the bars and chain and guide means for advancing the unconnected links to and 25 away from said pusher station.

4. In a knitting machine, the combination 30 of shiftable thread guide devices and pattern links for predeterminedly actuating the same, said links being unconnected, guide means for carrying the unconnected links into position for actuating the thread 35 guide devices, guide means for carrying said loose links away from said position and link actuating means at said operating position.

5. In a knitting machine, the combination 40 of superposed rows of thread guide devices, links for actuating the same, means for traversing said links in a substantially vertically extending circuit, means for effecting co-operative engagement of the links with said 45 devices including mechanism for temporarily removing said links from and returning them back into said circuit.

6. In a knitting machine, the combination 50 of loose pattern links, a guide way for said links, means for feeding the links to said guideway, means for advancing said links in said guideway and guide means positioned to receive the links at an advanced position in said guideway.

7. In a knitting machine, the combination 55 of pattern links, a guideway for receiving the same, a pusher for advancing the pattern links in said guideway, guide means extending from an advanced point in said guideway, said pusher having a stroke to carry the links as far as the guide means in its advancing movement and constructed to support the links in the forward travel to the 60 guide means but adapted to release the links to said guide means on the return travel of the same.

8. In a knitting machine, the combination 65 of a substantially horizontal way, a feeding-

guideway, a feeding out chute extending from a forward portion of the way, pattern links operable in said chutes and way, an impeller adapted to carry the links in said way from a position at the feeding-in chute to a position beyond the feeding out chute, said impeller having a cooperative engagement with the links to support the same in the forward stroke over the feeding out chute and to release the links into the feeding out chute on the return stroke. 70

9. In a knitting machine, the combination of a substantially horizontal way, a feeding-in chute at the rearward portion of said guideway, a feeding out chute extending from a forward portion of the way, pattern links operable in said chutes and way, an impeller adapted to carry the links in said way from a position at the feeding-in chute to a position beyond the feeding out chute, said impeller having a cooperative engagement with the links to support the same in the forward stroke over the feeding out chute and to release the links into the feeding out chute on the return stroke and stripper mechanism for definitely separating the links from the impeller in position to enter the feeding out chute. 80

10. In a knitting machine, the combination 85 of thread guide devices, pattern links for actuating the same, a pusher for advancing the pattern links to the thread guide devices, means for guiding the pattern links into position for actuation by said pusher, guide means for directing the links advanced by the pusher away from the pusher and mechanism for definitely shifting the links advanced by the pusher to said latter 90 guide means. 95

11. In a knitting machine, the combination 100 of thread guide devices, pattern links for actuating the same, a pusher for advancing the pattern links to the thread guide devices, means for guiding the pattern links into position for actuation by said pusher, guide means for directing the links advanced by the pusher away from the pusher, mechanism for definitely shifting the links advanced by the pusher to said latter guide 105 means and means for carrying the links from said latter guide means back to the first guide means. 110

In testimony whereof I affix my signature.
